UNITED STATES PATENT OFFICE.

LOUIS L. DRIGGS, OF NEW YORK, N. Y.

APPARATUS FOR FEEDING CARTRIDGES TO MACHINE-GUNS.

1,224,366.

Specification of Letters Patent.

Patented May 1, 1917.

Application filed July 15, 1916. Serial No. 109,590.

To all whom it may concern:

Be it known that I, LOUIS L. DRIGGS, a citizen of the United States, residing at New York, in the county of New York and State of New York, have invented certain new and useful Improvements in Apparatus for Feeding Cartridges to Machine-Guns; and I do hereby declare the following to be a full, clear, and exact description of the invention, such as will enable others skilled in the art to which it appertains to make and use the same.

My present invention relates especially to apparatus used in guns of the type of one inch caliber or thereabout, although the apparatus is adapted to use with smaller cartridges as well as larger.

My invention relates especially to that type of feeding device in which the cartridges are contained in a clip, and are held in place by resilient springs provided on the clip, and fed into the gun by tripping one of said springs and allowing the cartridges to be fed to the gun under the action of gravity.

My invention will be understood by reference to the accompanying drawings, in which:

Figure 1 shows a section through the upper part of the hopper of the gun showing the clip inserted therein, the section being along the line 1—1 of Fig. 2, looking in the direction of the arrows.

Fig. 2 shows a section along the line 2—2 of Fig. 1 and looking in the direction of the arrows, parts being broken away in both figures.

Fig. 3 is a detail view showing the detachable liner for the shell slide, parts being broken away.

Fig. 4 is a plan view of Fig. 3, and

Fig. 5 shows a front view.

Fig. 6 shows a side elevation of the clip before the cartridges are inserted therein.

Fig. 7 shows a section along the line 7—7 in Fig. 5, and looking down.

Fig. 8 is a detail showing one of the clip springs used for holding the cartridges in the clip; and

Figs. 9 and 10 are details showing the cam piece for camming open the clip spring, Fig. 9 showing a rear view and Fig. 10 a side elevation of said cam piece.

A represents the hopper which is applied to the gun in the usual way, and is provided

with the usual guide slots *a* for guiding the rims of the cartridge cases as the projectile is fed to the gun. These guide slots may be preferably reinforced by a hard metal liner *B* having the flanges *b* and lips *b'*, as shown more clearly in Fig. 4.

C represents the clip, the body portion of which is composed of a single sheet of metal, preferably pressed steel, which is rolled and pressed to the desired form shown in Figs. 5, 6 and 7.

The bottom 1 of the plate is flanged outward as at 2, see Fig. 7, to form longitudinal stiffening ribs, and also to provide a groove 3 in which the primer of the cartridge case is held clear from any possible contact with the thin metal wall of the clip. The sheet is flanged at right angles, as at 4, and provided with overhanging lips 5, thus forming guide grooves 6 for the rim of the cartridge case.

Attached to each end of the clip at the rear thereof, I provide a spring *D* having the bent over end *d* normally closing the end of the slots 6. This spring is provided with laterally projecting ears *d'*, adapted to engage the cam piece *E*, as hereinafter described. These springs may be secured to the bottom of the clip in any convenient way, as by welding, or by means of the rivets *d*² passing through the apertures *d*² in the spring *D* and through the holes 7 in the base of the clip.

It will be seen that these springs will normally tend to spring into the position in Fig. 6, and to close the ends of the slots 6, thus holding the cartridges securely in the clip. These springs are preferably symmetrically disposed at opposite ends of the clip, so that the clip may be fed into the hopper from either end without requiring the loader to stop to think which end should go first.

When the clip is placed in the hopper for the loading position, the ears *d'* on the lower spring of the clip engage the cam faces *e'* on the arms *e* of the cam piece *E*, and the spring assumes the position shown in Fig. 2, opening the end of the clip and allowing the cartridges to fall by gravity therefrom.

This cam piece *E* is secured in the hopper in any convenient way, as by means of bolts or rivets *e*² passing through the bolt holes *e*².

By making the clips of pressed sheet

metal, they can be manufactured very cheaply; and by having the flanges 2 and groove 3 in the bottom of the clip, there is not only additional rigidity added to the 5 clip, but the primer is held clear of the bottom of the clip and thus protected against accidental explosion.

While the guide grooves 6 for the rim of the cartridge case may be made just deep 10 enough to fit the axial length of the rim of the cartridge case, I prefer to make these grooves deep enough to permit the overlapping of the rims of the cartridge cases as shown in dotted lines in Figs. 5 and 7, 15 whereby it is possible to shorten the clip for the same number of cartridges, and the cartridges are held more firmly in the clip when the latter is not in the gun.

It will be obvious that various modifications might be made in the herein described apparatus and in the construction, combination and arrangement of parts which could be used without departing from the spirit of my invention.

Having thus described my invention, what I claim and desire to secure by Letters Patent of the United States, is:

1. A cartridge clip comprising a body portion made of a single strip of sheet metal having an outwardly projecting trough along the central longitudinal axis thereof, the said trough being rectangular in cross section so that its sides may form stiffening ribs for the clip, and its hollow 30 portion may mask the primer of the cartridge, the said body portion being also provided with guide grooves at each side thereof, said guide grooves being also rectangular in cross section whereby additional 35 stiffening ribs are provided for the sides of said clip, and leaf springs secured to the exterior of said rectangular trough, said springs having lips projecting inward in

the path of the rims of the cartridge cases, substantially as described.

2. A cartridge clip comprising a body portion made of a single strip of sheet metal having an outwardly projecting trough along the central longitudinal axis thereof, the said trough being rectangular in cross section so that its sides may form stiffening ribs for the clip, and its hollow portion may mask the primer of the cartridge, the said body portion being also provided with guide grooves at each side thereof, said guide 50 grooves being also rectangular in cross section whereby additional stiffening ribs are provided for the sides of said clip, said guide grooves being of sufficient depth to receive the overlapping rims of adjacent 55 cartridge cases held in said clip, and leaf springs secured to the exterior of said rectangular trough, said springs having lips projecting inward in the path of the rims of the cartridge cases, substantially as described.

3. Apparatus for feeding cartridges to guns comprising a hopper provided with guide grooves for the rims of the cartridge cases, a cartridge clip having grooved sides 70 adapted to register with the guide grooves in the hopper, said clip also having a channeled bottom adapted to mask the primers of the cartridge cases, leaf springs secured to the channeled bottom of said clip and 75 having lips projecting in front of said grooves in the clip, said springs being provided with laterally projecting ears, and a U-shaped cam piece mounted in said hopper and having wedged faces adapted to 80 engage the ears of one of said springs and to withdraw said spring, thus opening that end of the clip, substantially as described.

In testimony whereof, I affix my signature.

LOUIS L. DRIGGS
